UNITED STATES PATENT OFFICE.

JOHN M. SUNDEAN, OF MARSHALL, MINNESOTA.

SHOE.

1,087,517..

Specification of Letters Patent. Patented Feb. 17, 1914.

Application filed November 4, 1913. Serial No. 799,239.

To all whom it may concern:

Be it known that I, JOHN M. SUNDEAN, a citizen of the United States, residing at Marshall, in the county of Lyon and State 5 of Minnesota, have invented a new and useful Shoe, of which the following is a specification.

The present invention appertains to footwear, and aims to provide novel means for 10 stitching the upper or vamp to the outsole, in order that the shoe or boot may possess a high degree of flexibility and durability, and in order that the structure will be relatively simple and inexpensive, as well as 15 comfortable.

With the foregoing general object outlined, and with other objects in view, which will be apparent as the nature of the invention is better understood, the present invention 20 resides in the combination and arrangement of parts and in the details of construction hereinafter described and claimed, it being understood that changes in the precise embodiment of the invention herein 25 disclosed, can be made within the scope of what is claimed, without departing from the spirit of the invention.

The invention has been illustrated in its preferred embodiment in the accompanying 30 drawing, wherein:

Figure 1 is a fragmental perspective view of the toe of a shoe constructed in accordance with the present invention. Fig. 2 is a 35 sectional view of the outsole, welt, and upper or vamp in separated positions. Fig. 3 is a view similar to Fig. 2, illustrating the upper and outsole stitched to the welt. Fig. 4 is a similar view of the said parts finished.

In carrying out the present invention, the 40 shoe is provided with an outsole 1, the upper and lower faces of which are left plain, or uncut. The welt 2 has its inner edge skived or cut away, as at 4, to form a skive or bevel, upon which the inturned edge of 45 the upper or vamp 3 is adapted to rest. The margin or edge of the outsole 1 is skived or split, as at 5, from a point directly adjoining the upper face of the outsole, diagonally inward and downward, to provide 50 the leaf or flap 6 having a relatively thick basal portion, and a relatively thin edge.

In assembling the upper or vamp, welt, and outsole, the inturned edge of the upper rests upon the skived surface or bevel 4 of

the welt, and is stitched thereto, by means 55 of one or more seams 7, two of such seams or lines of stitches being illustrated, although their numbers vary according to the circumstances. After the upper has been stitched to the inner edge portion of the 60 welt, the outer edge portion of the welt is placed upon the leaf or flap 6, the leaf or flap being turned upward, as seen in Fig. 3, to permit the welt and leaf 6 to be stitched together, as at 8. As illustrated, a second 65 seam or line of stitches 8' is employed for securing the free edges of the welt and leaf 6 to the edge of the outsole proper, although cement alone may be employed for securing the leaf 6 down. With the double seam 70 8-8', it will be obvious that the inner seam will serve to rigidly secure the welt to the outsole, while the outer seam will secure the edge portions of the welt and outsole together in such a manner as to give a neat 75 appearance and finish to the shoe or boot. The slit 5 being disposed as above described, will locate the slit or skive in the upper one third portion of the outsole, and as a result, the marginal portion of the outsole which 80 is rigid, will not be appreciably weakened, and at the same time, efficient means are provided for stitching the welt to the outsole. The inner portion of the slit 5 will be deep enough, to permit the welt to be effectively stitched to the basal portion of the leaf or flap 6, thereby securing firmness between the welt and outsole.

An insole 9 is preferably employed, the same resting upon the outsole 1, and the 90 inturned edge of the upper, the insole being preferably loose, in order to be exceedingly flexible and comfortable. A cork filler 10 is preferably cemented or otherwise secured to the bottom of the insole 9 to increase the 95 comfort and flexibility of the sole as a whole. The inturned edge of the upper preferably extends beyond the edge of the welt 2, and the filler 10 preferably occupies the space between the edge portion of the 100 upper. The insole may be dispensed with, if desired, although it is of advantage, inasmuch as it permits of half-soling the shoe, the nails being readily engaged through the edge portions of the upper and insole. 105

From the foregoing taken in connection with the drawing, the other advantages of the present structure will be obvious, with-

out comment, it being observed that the objects aimed at have been carried out satisfactorily.

Having thus described the invention,
5 what is claimed as new is:—

In a shoe, an outsole having a marginal slit, the slit extending from a point directly adjoining the upper face of the outsole diagonally inward and downward, to
10 provide a leaf having a relatively thick basal portion and a relatively thin edge; a

welt, and an upper having its edge turned in and stitched upon the welt, the welt being stitched to the said leaf.

In testimony that I claim the foregoing 15 as my own, I have hereto affixed my signature in the presence of two witnesses.

JOHN M. SUNDEAN.
